J. G. FOGARTY,
EXCAVATING MACHINE,
APPLICATION FILED NOV. 14, 1912.

L,229,600.

Patented June 12, 1917.

UNITED STATES PATENT OFFICE.

JOHN G. FOGARTY, OF CARTHAGE, NEW YORK, ASSIGNOR TO JOHN FOGARTY CO., INC.,
OF ROCHESTER, NEW YORK, A CORPORATION OF NEW YORK.

EXCAVATING-MACHINE.

1,229,600.

Specification of Letters Patent. Patented June 12, 1917.

Application filed November 14, 1912. Serial No. 731,258.

To all whom it may concern:

Be it known that I, JOHN G. FOGARTY, of Carthage, in the county of Jefferson and State of New York, have invented certain new and useful Improvements in Excavating-Machines; and I do hereby declare the following to be a full, clear, and exact description of the same, reference being had to the accompanying drawings, forming a part of this specification, and to the reference-numerals marked thereon.

My invention relates to excavating machines, and it has for its object to afford a construction, which is adaptable to the type of machine involving a rigid connection between the bucket and the boom, whereby the bucket may be adjusted at different angles relatively to the boom, in order to permit working in different positions without moving the entire machine. To these and other ends the invention consists in certain improvements and combinations of parts all as will be hereinafter more fully described, the novel features being pointed out in the claims at the end of the specification.

In the drawings:

Figure 1 is a side elevation of a machine embodying my invention, showing the outer end of a boom, and bucket attached; Fig. 2 is a view of the parts shown in Fig. 1 partly in end elevation and partly in section on the line 2^a—2^a of Fig. 1;

Fig. 3 is a sectional view on the line 3^a—3^a of Fig. 2, showing the bucket adjusted at right angles to its position in the previous figures, and

Fig. 4 is a transverse vertical sectional view on the line 4^a—4^a of Fig. 3.

Similar reference numerals throughout the several figures indicate the same parts.

In the arrangement, according to the present embodiment, 1 designates the boom of the machine, which may be of any improved form, and is provided at its outer end with the arms 2 upon which the support for the bucket is mounted. Said support preferably comprises a base portion 3 and vertical standards 4 mounted thereon which are pivotally connected to the arms 2. The support has mounted thereon the carrier to which the bucket is attached and which may be adjusted with relation to the support as will now be described.

To this end, the carrier embodies a plate 5 provided with an annular, inwardly pro-

jecting flange 6 which is preferably detachable from the plate 5 and held in engagement therewith by means of the bolts 7. The flange 6 is arranged to engage the upper edge of the base 3 of the support, as shown in Fig. 4, thus holding the carrier upon the support and permitting it to turn relatively to the same. The carrier may thus be rotated through any angle, to change its position, and may be held in the desired adjustment by a suitable locking means, preferably consisting of a removable pin 8 adapted to engage an opening in the carrier and any one of a series of openings 9 in the base of the support.

The bucket comprises a pair of scoop members 10 which are connected by means of links 11 to the carrier 5, the latter being provided with the bolts 12 upon which said links are pivotally supported. The scoop members 10 are pivotally connected together by means of a pin 13, co-operating with lugs 14 upon the scoop members and also with the ears 15 formed upon a holder which includes a base 16 and upstanding walls 17 between which are mounted the pulleys 18 for guiding the operating cable, the latter being connected to the holder at 19.

The carrier 5 is provided on its under surface with arms 20 between which are mounted the pulleys 21, which, it will be noted, are arranged to one side of the center of the carrier as shown in Figs. 2 and 4. The carrier and the base of the support are provided with central openings through which passes the operating cable 22, the latter being held in proper position by means of the guide pulleys 23 arranged in co-operative engagement upon the support, and mounted on the plate 24 which is secured to the base 3. The standards 4 are provided with projections 25 to receive the bearing 26 upon which is mounted the pulley 27, over which the operating cable passes to the boom.

In the operation of the machine, when it is desired to change the position of the bucket, the pin 8 is removed and the carrier may be turned upon the support until the desired angle of adjustment is obtained. The pin 8 being again inserted, locks the carrier upon the support, holding it rigidly in its adjusted position, while at the same time permitting it to be quickly and readily turned to change its angular relationship, when the conditions require it.

I claim as my invention:

1. In a hoisting machine, the combination with a boom having a support provided with a circular base, of a carrier embodying a flange in engagement with the upper face of the base, the base having a series of openings extending transversely of its periphery, the carrier having an opening adapted to be aligned with one of said openings in the base, a pin coöoperating with the openings in the carrier and base respectively, and a bucket suspended from the carrier.
2. A hoisting machine comprising a boom, a support connected therewith having a circular base, a carrier having a flange in rotative engagement with the base, a bucket suspended from the carrier, arms extending beneath the carrier, pulleys mounted upon the arms, a holder connected with the bucket, pulleys on the holder and a cable connected with the holder and extending over each of the pulleys and through the carrier and support to the boom.
3. A hoisting machine comprising a boom, a support connected therewith having a circular base, a carrier having a flange in rotative engagement with the base, a holder beneath the carrier, buckets pivotally connected with the holder upon opposite sides thereof, links connecting the buckets with the carrier, pulleys mounted upon the carrier and holder and a cable having one end secured upon the holder and extending over the pulleys through the center of the carrier to the boom.
4. In an excavating machine, the combination with a boom, of a support pivoted on said boom and having a centrally disposed opening in its base, a carrier rotatively mounted on the support and provided with an opening in alignment with said opening in the support, a bucket mounted on the carrier and a bucket cable passing from the boom through said openings in the support and carrier and extending downwardly toward the bucket in a vertical line.
5. In an excavating machine, the combination with a boom, of a support mounted on said boom and having a centrally disposed opening in its base, a carrier mounted on the support having an opening in alignment with the opening in the support, a bucket comprising a pair of bucket members pivoted together, connecting rods secured to said bucket members and pivoted to the aforesaid carrier, a pulley mounted on the under side of the carrier, and a bucket cable passing from the boom through said openings in the support and carrier extending downwardly toward the bucket in a vertical line and coöperating with the aforesaid pulley on the carrier.

JOHN G. FOGARTY.
